TYPOGRAPHICAL MACHINE

Walter H. Medford, Brooklyn, N. Y.

Application January 15, 1938, Serial No. 185,084

5 Claims. (Cl. 199—53)

My invention relates to a new and improved guard for a typographical machine.

One of the objects of my invention is to improve that type of typographical machine which is known in the trade as "Intertype No. H."

Another object of the invention is to provide a guard which is connected to and which moves in unison with the pot which contains the molten metal, and to provide automatic means whereby the cover of said guard is moved into operative position over the mold in which the matrices are located, before the slug is molded. Said cover is maintained in position while the mold is being filled with the molten metal, so that the molten metal cannot squirt upwardly from the mold, if the matrices and the spacers do not completely fill the mold.

Another object of the invention is to provide a device of this type, whereby relief means are provided so as to prevent the breakage of the guard, if the movement of the guard to its operative position is obstructed by means of the defective operation of the machine.

Another object of the invention is to provide a simple and efficient mechanism which can be attached to existing machines and which will operate properly in the very limited space in which such an attachment can be installed.

Other objects of the invention will be set forth in the following description and drawings which illustrate a preferred embodiment thereof, it being understood that the above statement of the objects of my invention is intended generally to explain the same without limiting it in any manner.

Fig. 1 is a perspective view showing the guard detached from the typographical machine.

Fig. 2 is a perspective view of the bracket which is fixed to the frame of the machine and which causes the movement of the guard cover to the operative position.

Fig. 3 is a sectional view on the line 3—3 of Fig. 1.

Fig. 4 is a sectional view on the line 4—4 of Fig. 1.

Fig. 5 is a side elevation showing the attachment and certain adjacent parts of the typographical machine. In Fig. 5 the guard is shown in its inoperative position.

Fig. 6 is the same as Fig. 5 save that in Fig. 6 the guard is shown in its operative position.

Fig. 7 shows the position of the guard when a part of the machine interferes with the movement of the guard to the fully operative position which is shown in Fig. 6.

Fig. 8 is a front elevation, taken on the line 8—8 of Fig. 5.

Fig. 9 is a sectional view on the line 9—9 of Fig. 8. In Fig. 9 the guard is shown in its inoperative position.

Fig. 10 is the same as Fig. 9 save that in Fig. 10 the guard is shown in its operative position.

Fig. 11 is a sectional view on the line 11—11 of Fig. 8.

Fig. 12 is a sectional view on the line 12—12 of Fig. 11.

In operating a typographical machine of the aforesaid type, the mold may have one or more spaces, due to various causes, through which the molten metal can squirt upwardly, when said lead is delivered under usual pressure to said mold. This molten lead can seriously injure the operator, as it spurts upwardly to such a height that it can fall back upon the operator's head or hands.

This defect has rendered the operation of such machines both uncertain and hazardous.

It has been proposed to use a partial fixed guard over the top of the mold, but this is ineffective, and it interferes with the proper operation of the machine.

According to my invention a movable cover is provided which is mounted on the pot which contains the molten metal, and said cover may be normally urged to the inoperative position so that it does not interfere with the proper operation of the machine, and said cover is moved automatically into its operative position over the mold before the molten metal is delivered to the mold. Likewise said cover is maintained automatically in its operative position, during the molding operation, until the molten metal has solidified in the mold.

Referring to Fig. 1, this shows a guard-cover 1 having an end portion 1a integral with said guard-cover 1. Said members 1 and 1a are connected to arms 2 and 2a which are turnably connected by means of pivot pins 3 and 3a, to the ends of a frame 4.

The pins 3 and 3a may be stud-pins which are fixed to the frame 4. The arm 2a is fixed to the gear 5 so that said gear 5 turns in unison with the movement of the guard-cover. The gear 5 meshes with the gear teeth of a sector 6. The gear teeth of the sector 6 have a much larger pitch diameter than the pitch diameter of the teeth of the gear or pinion 5.

Therefore the angular turning movement of the sector 6 is much less than the angular turning movement of the gear or pinion 5.

The sector 6 is turnably mounted upon a stud pin 7 which is fixed to the adjacent portion of the frame 4. The gear ratio between the gear 5 and the sector 6 may be about one to four.

5 The sector 6 is provided with an upstanding pin 8. This pin 8 is mounted upon an angular head 6a of the sector 6. The frame 4 is mounted upon the pot 9, which is moved to and fro in the usual manner. Said pot contains the molten metal.

I have not illustrated the details of construction of the pot 9 and the other well known accessory parts of a typographical machine.

15 The invention is illustrated particularly in connection with the typographical machine which is known in the trade as "Intertype No. H." This pot 9 is provided with the usual openings 10 through which the molten metal is delivered to the mold.

20 In Fig. 8, only some of the casting holes 10 are shown, as this detail is well known.

In Fig. 5, the pot 9 is shown in its inoperative or non-molding position. In Fig. 10 said pot 9 is shown in its operative or molding position.

25 The pot 9 is supported in the usual manner upon an arm 9a, which is provided with a yoke-shaped end, to which a supplemental member 11a is suitably connected.

Bearing screws 11 have their ends fitting in 30 suitable recesses which are provided in a shaft 12, so that the pot 9 can be rocked towards and away from the operative casting position which is shown in Fig. 6.

35 Referring to Fig. 2 and Fig. 8, the frame F of the machine has the arm 14 fixed thereto. The arm 14 is provided with a slot 14a by means of which said arm 14 can be adjustably clamped to the frame F, by means of clamping members which extend through said slot 14a.

40 As shown in Fig. 2, the arm 14 has a lateral pin 15 fixed thereto. This pin 15 is integral with a head 16 which has an upstanding pin 17 fixed thereto. The pins 8 and 17 are provided with lateral grooves, as shown in Fig. 1 and Fig. 2.

45 As shown in Figs. 9 and 10, a tension spring 18 (a part of said spring being shown in Fig. 12) is connected to said pins 8 and 17. Said tension spring 18 tends to maintain the guard-cover 1 normally in the inoperative position which is 50 shown in Fig. 9.

The arrows indicated in Fig. 9 show the respective directions in which the spring 18 tends to turn the sector 6 and the guard-cover 1.

As shown in Fig. 2, the head 16 is provided 55 with a plunger 19. As shown in Fig. 12, the head 16 is provided with a suitable recess. A part of the plunger 19 is located in said recess and said plunger 19 fits slidably within said recess. Said plunger 19 has a reduced shank 20 which passes through the end wall of the head 16.

60 A helical compression spring 21 is coiled around the shank 20 so that said compression spring tends to force the plunger 19 out of the head 16. The projecting portion of the shank 20 is externally threaded, and one or more lock nuts 22 limit the outer movement of the plunger 19, under the force of the compression spring 21.

65 As shown in Fig. 10, when the pot 9 is moved to its molding position, the head 6a abuts the outer end of the plunger 19, before the pot has moved to its final molding position, and before the molten metal is delivered from said pot.

70 75 As the pot is moved to its molding position,

the tension of the spring 18 is lowered, as can be seen by comparing Fig. 9 and Fig. 10.

When the plunger 19 abuts the head 6a, the further movement of the pot 9 to its molding position, causes the sector 6 to turn, as indicated by the respective arrows in Fig. 10, so that the guard-cover 1 is turned to its operative position over the mold, in the direction of the respective arrow indicated in Fig. 10.

As shown in Fig. 7, if the machine is not 10 operating perfectly, an arm of the machine may remain in the path of the cover. For example, Fig. 7 shows the arm 23 of the delivery slide, in the path of movement of the guard-cover, this being one of the contingencies which may arise 15 due to imperfect operation of the typographical machine. Under such circumstances, the compression spring 21 yields sufficiently so as to prevent the parts from breaking.

Figs. 5-7 show the yoke 24, which forms part of 20 the delivery slide.

In order to show the relation of the improvement to the standard parts of the aforesaid typographical machine, I have shown the elevator E in Figs. 5 and 6. This elevator delivers the matrices to the mold 30, in which the slug is molded.

Certain conventional parts of the typographical machine have been illustrated in broken lines, in order to bring out the invention more clearly.

In the specific machine which has been illustrated, the mold is stationary and the pot is moved. This may be defined by stating that there is relative movement between the pot 9 and the mold 30 and the invention generally covers any machine in which there is relative 35 movement between the pot and the mold, and in which a guard is moved to intercept molten metal which may be squirted out of the mold when the pot and the mold are in the casting position illustrated in Fig. 6 and in Fig. 10.

40 For convenience, the member 19 may be designated as an abutment member and the gear 5 may be designated as a first gear member and the sector 6 may be designated as a second gear member. It will be noted that the abutment member 19 contacts with the second gear member 6 at a predetermined point in the movement of the guard 9 towards the mold 30, so as to cause the guard 9 to be moved to its operative position before the casting is begun. Likewise the abutment member 19 is yieldingly connected to the frame so as to stop the positive movement of the guard to its operative position, if said movement of the guard is obstructed.

45 I have shown a preferred embodiment of my 55 invention, but it is clear that numerous changes and omissions can be made without departing from its spirit.

I claim:

1. In a typographical machine which has a 60 mold and which has a pot which is movable towards and away from said mold, a guard pivotally mounted on said pot, and means operative to turn said guard relative to said pot so that the guard is moved over the top of said mold when 65 the pot is moved to casting position.

2. In a typographical machine which has a mold and which has a pot which is movable towards and away from said mold, a guard pivotally mounted on said pot, and means operative to turn 70 said guard relative to said pot so that the guard is moved over the top of said mold when the pot is moved to casting position, said means including an abutment member which is connected to the frame of the machine.

3. In a typographical machine which has a mold and which has a pot which is movable towards and away from said mold, a guard pivotally mounted on said pot, and means operative to turn said guard relative to said pot so that the guard is moved over the top of said mold when the pot is moved to casting position, said means including an abutment member which is connected to the frame of the machine, said abutment member being yieldingly connected to the frame of the machine so that it can yield sufficiently to cause the guard to remain in inoperative position if the movement of the guard to its operative position is obstructed.
- 5 5
5. In a typographical machine which has a mold and a pot which is movable towards and away from the mold, a guard pivotally mounted on the pot, a first gear member also mounted on the pot and connected to said guard and turnable in unison with the guard, a second gear member 10 also mounted on the pot and intermeshing with the first gear member, the second gear member having gear teeth whose pitch diameter exceeds the pitch diameter of the gear teeth of the first gear member, a spring having one end connected to the second gear member and having the other end connected to the frame of the machine, said spring being operative to turn the second gear member, when the pot is at its maximum distance from the mold so as to keep the guard 15 spaced from said mold, and an abutment member connected to the frame of the machine and adapted to abut the second gear member at a predetermined point in the movement of the pot towards the mold so as to turn the second gear member 20 and to cause the guard to be turned to its operative position over the top of the mold.
- 10 10
10. 4. In a typographical machine which has a mold and a pot which is movable towards and away from the mold, a guard pivotally mounted on the pot, a first gear member also mounted on the pot and connected to said guard and turnable in unison with the guard, a second gear member 15 also mounted on the pot and intermeshing with the first gear member, the second gear member having gear teeth whose pitch diameter exceeds the pitch diameter of the gear teeth of the first gear member, a spring having one end connected to the second gear member and having the other end connected to the frame of the machine, said spring being operative to turn the second gear member, when the pot is at its maximum distance from the mold so as to keep the guard 20 spaced from said mold, and an abutment member connected to the frame of the machine and adapted to abut the second gear member at a predetermined point in the movement of the pot towards the mold so as to turn the second gear member 25 and to cause the guard to be turned to its operative position over the top of the mold.
- 20 20
20. 25. 5. In a typographical machine which has a mold and a pot which is movable towards and away from the mold, a guard pivotally mounted on the pot, a first gear member also mounted on the pot and connected to said guard and turnable in unison with the guard, a second gear member 30 also mounted on the pot and intermeshing with the first gear member, the second gear member having gear teeth whose pitch diameter exceeds the pitch diameter of the gear teeth of the first gear member, a spring having one end connected to the second gear member and having the other end connected to the frame of the machine, said spring being operative to turn the second gear member, when the pot is at its maximum distance from the mold so as to keep the guard 30 spaced from said mold, and an abutment member connected to the frame of the machine and adapted to abut the second gear member at a predetermined point in the movement of the pot towards the mold so as to turn the second gear member and to cause the guard to be turned to its operative position over the top of the mold.
- 25 25
25. 30. 30. 30.
